CLAIM

The ornamental design for an agglutination viewer with fiber optic light pipe and magnetic magnifying mirror, as shown and describe.

DESCRIPTION

FIG. 1 is a left front perspective view of an agglutination viewer with fiber optic light pipe and magnetic magnifying mirror showing our new design;

FIG. 2 is a right side elevational view thereof;

FIG. 3 is a top plan view thereof;

FIG. 4 is a bottom plan view thereof;

FIG. 5 is a front elevational view thereof; and,

FIG. 6 is a rear elevational view thereof.
